UNITED STATES PATENT OFFICE.

JOSEPH B. MCENALLY, OF CLEARFIELD, PENNSYLVANIA.

TEMPORARY BINDER.

SPECIFICATION forming part of Letters Patent No. 269,694, dated December 26, 1882.

Application filed August 25, 1882. (Model.)

To all whom it may concern:

Be it known that I, JOSEPH B. MCENALLY, of Clearfield, in the county of Clearfield and State of Pennsylvania, have invented a new and Improved Temporary Binder, of which the following is a full, clear, and exact description.

The object of my invention is to materially facilitate the temporary binding of books, pamphlets, documents, &c.

Reference is to be had to the accompanying drawings, forming part of this specification, in which similar letters of reference indicate corresponding parts in all the figures.

Figure 1 is an inside elevation of my improved binder, showing it opened. Fig. 2 is a horizontal sectional view of the same on the line *xx*, Fig. 1. Fig. 3 is a sectional view of the same on the line *yy*, Fig. 2.

The covers *A* are united by a flexible back, *B*, in the usual manner. From the inner surface and near the inner edge, *C*, of one cover *A* two or more eyes or loops, *D*, project. From the corresponding edge of the inner surface of the other cover two long flexible prongs or fasteners, *H*, project. A metal strip, *E*, is provided with two apertures, *F*, corresponding in position with the fasteners *H* and with two longitudinal slots, *G*, corresponding in position with the eyes *D*. Adjoining to each slot *G* a hook, *J*, is pivoted to the strip *E*, so that the said hooks can be passed through the eyes *D* after the same have been passed through the

slots *G*. The flexible prongs or fasteners *H* are passed through the sheets *K*, that are to be bound, and then through the apertures in the strip *E*, which is placed on that leaf farthest from that cover to which the fasteners *H* are secured. After the prongs have been passed through the apertures *F*, they are bent down flat on the strips *E*, the hooks *J* of which are on the inner or under surface. The leaves are thus attached to one cover, and the other cover is then folded down over them, so that the eyes *D* will pass through the slots *G*, upon which the hooks *J* are turned to pass through those parts of the eyes projecting from the inner surface of the strip *C*, whereby the other cover will also be held to the sheets.

Books, pamphlets, and other papers and documents can thus be bound temporarily very easily and rapidly, and both covers will be held to the papers that are to be bound.

Having thus described my invention, I claim as new and desire to secure by Letters Patent—

In a binder, the combination, with the covers *A* and the back *B*, of the fasteners *H*, the eyes *D*, and the strip *E*, provided with slots *G* and hooks *J*, substantially as herein shown and described, and for the purpose set forth.

JOSEPH B. MCENALLY.
